UNITED STATES PATENT OFFICE

ANDRÉ ANTOINE CHAUVIN, OF PARIS, FRANCE

INDEX CARD

Application filed June 18, 1931, Serial No. 545,251, and in France December 17, 1930.

This invention relates to card indexes and the like of the type in which the cards are contained in shallow drawers or the like, so that the cards occupy horizontal or substantially horizontal planes and are superposed one above the other, and in which means are provided for spacing the superposed cards in such a manner that the lower portion of one card projects a desired distance beyond the corresponding portion of the card immediately above it, so that the lower portions of the whole of the cards in the shallow drawers or the like are readily visible at one and the same time.

15 The present invention has for an object to provide cards or the like for utilization in such card indexes.

It has for a further object so to form such cards that they are provided with integral means for controlling the overlap between succeeding cards, that is the amount that the lower card projects beyond the one immediately above it.

20 A still further object is to provide each card with integral means for controlling the amount of overlap of such a nature that the amount of overlap can be varied within two limits, that is to say a card can be set so that the amount by which the card below it projects can be a certain predetermined dimension, or another predetermined dimension.

Another object is to form the upper parts of such cards with laterally projecting portions for engagement with grooves or the like in the side walls or equivalent parts of the containing drawers.

25 A further object is to provide such cards with means for facilitating their turning up, such for example as a row of perforations near to the upper portion, and for a still further object to form such cards with means for carrying other cards, paper slips or the like.

The above and other objects will appear 40 in the following specification.

In order that the invention may be better understood it will now be described with reference to the accompanying drawing in which:

50 Fig. 1 shows a somewhat diagrammatic per-

spective view of an index card having two top folds arranged stepwise one above the other and illustrating a preferred embodiment of the invention.

Fig. 2 shows a fragmentary perspective view of an upper portion of an index card according to another embodiment of the invention, and

Fig. 3 shows a similar view to Fig. 1 of a still further form.

Fig. 4 is a face view of an index card in accordance with the invention.

Fig. 5 is an end view of Fig. 4. The card according to Fig. 1 is formed from a thickness of strong paper or the like and comprises a doubled portion 1 coming at the upper edge which is folded over and stuck together (the sticking together is not illustrated in the drawing for the sake of clearness). Below the portion 1, the card is again doubled at the part marked V', the doubled portion being stuck together (this sticking together is not shown in the drawing for the sake of clearness) to form what may be termed a hook or step 2, the main body 4 of the card extending below this hook 2.

The other portion of the card from the folded part 1 is doubled back on itself as shown at V in the drawings and stuck together to form a step or hook 3 as shown, which comes a desired distance D above the step or hook 2.

30 The two lateral edges of the portion 4 forming the card proper are slightly cut away so that this portion 4 is of less width than the upper part, so that these upper portions project at the sides and can be utilized as guides for the card in lateral grooves provided in the sides of the drawer.

35 5 are slits which may be provided in the body of the card 4 to receive slips of paper or the like if desired.

6 is a row of perforations coming just below the level of the lower edge of the portion V', 40 for facilitating the turning up of the card, that is to say the perforations give a slight weakening to this portion of the card, enabling it to be turned up and hinged around the line of perforations.

As will be realized, the card proper can be made without the slits 5 and if desired without the perforations 6, although the latter are preferably included.

5 Figs. 4 and 5 show the shape of the card more clearly, the folded head portion 1 being extended laterally somewhat beyond the side of the card proper 4.

In Fig. 5, which is an end view, the head 10 is constructed substantially as shown in Fig. 1 of the drawing but after the parts have been stuck together, the head being folded substantially in the form of an inverted V.

One fold 2 of the card diverges from a position intermediate of one of the arms of the V and it will be understood that in assembling successive cards to form a card index, they can either be assembled so that the head or outer apex of one card passes into the folded 20 portion 2 of the card, or alternatively it may pass to the folded apex 3 of the V, and in this way it is possible to obtain two different degrees of spacing of the successive cards. It will be understood that it is necessary for the 25 cards to be reversed in order to obtain the different spacings.

By this means it will be realized that not only is the overlap of the cards controlled by the cards themselves, but that a certain adjustment in this overlap is possible by the provision of the two spaced steps or hooks 2 and 3.

The drawer may be filled with cards according to requirements, the overlap being 35 arranged according to the hook 2 or 3 of each particular card placed in position, and when the drawer is filled, it will be realized that the bottom portions of all the cards therein can readily be seen.

40 The card shown in Fig. 2 is substantially similar to that shown in Fig. 1, with the exception that it is formed from a single thickness doubled upon itself, the upper part giving the two portions V and V' which define 45 the spaced steps 2 and 3.

Again, in Fig. 3, the construction is similar to Fig. 1, with the exception that the portion V is formed from a single thickness, the step 3 being constituted where the portion V joins 50 the upper doubled portion 1 which is stuck together.

The invention is not limited to the precise forms or details of construction described, as these may be varied to suit particular cases.

55 What I claim and desire to secure by Letters Patent of the United States of America is:—

1. A card for card indexes of the type set forth, formed with two folded portions, the 60 fold of one of which is spaced from the upper edge a desired distance and the fold of the other of which is spaced from the upper edge a different desired distance, each said folded portion forming a hook adapted to engage with the upper edge of the next succeed-

ing card to determine the amount of overlap between the two cards, for the purposes set forth.

2. A card for card indexes as claimed in claim 1, in which one of the folded portions 70 comes on one side of the card and the other folded portion on the other side of the card, and in which the upper portion of the card projects laterally to a slight extent on each side beyond the lower portion, for the purposes set forth. 75

3. A card for card indexes as claimed in claim 1, in which one of the folded portions comes on one side of the card and the other folded portion on the other side of the card, 80 the upper portion of the card projecting laterally to a slight extent on each side beyond the lower portion, and in which a row of perforations is provided in the card just below the lower edge of the lower hook, for 85 the purposes set forth.

4. A card for card indexes as claimed in claim 1, in which one of the folded portions comes on one side of the card and the other folded portion on the other side of the card, 90 the upper portion of the card projecting laterally to a slight extent on each side beyond the lower portion, a row of perforations being provided in the card just below the lower edge of the lower hook, and in which the 95 lower portion of the card is formed with slits to receive paper slips, for the purposes set forth.

5. An index card of the type set forth, having a folded head in the form of an inverted V, the card proper diverging from one arm of said V at an intermediate position, whereby the head of a succeeding card may enter said head up to the apex of the V or up to the position where the card proper 105 diverges from the arm of the V. 100

In witness whereof I affix my signature.

ANDRÉ ANTOINE CHAUVIN.
